UNITED STATES PATENT OFFICE.

WILLIAM H. GINDER, OF HADDONFIELD, NEW JERSEY, ASSIGNOR, BY MESNE ASSIGNMENTS TO ELECTRO MANUFACTURING COMPANY OF AMERICA.

PORTABLE FAN.

Application filed August 25, 1927. Serial No. 215,435.

This invention relates to portable fans adapted for use in offices and households, etc. The principal object of the invention is to provide a fan which will create a continuous circulation of air in all directions radially from the axis of the fan and substantially parallel to the plane of rotation of the fan, whereby all persons seated around a table, upon which the fan is placed, will be aware of such air circulation.

Another object of the invention is to so construct the device that loose papers lying on the table, upon which the fan is placed, will not be disturbed by the circulation of air created by the fan.

Another object of the invention is to construct the device in such a manner as to permit of its usage as a base for a table lamp, ash receiver, flower holder, etc.

0 The construction of my invention will be fully disclosed hereinafter, reference being had to the accompanying drawings, of which:

Fig. 1 is a side elevation of my improved fan;

5 Fig. 2 is a plan view;

Fig. 3 is a sectional elevation of the air deflecting cone employed in my device;

Fig. 4 illustrates the deflecting cone with a lamp attachment located therein;

Fig. 5 illustrates a flower holder attachment adapted to be placed in the air deflecting cone;

Fig. 6 illustrates an ash receiver attachment;

Fig. 7 is a plan view of a modified form of air deflecting cone;

Fig. 8 is a section on the line 8—8, Fig. 7;

Fig. 9 is an inverted plan view of another form of air deflecting cone;

Fig. 10 is a section on the line 10—10, Fig. 9, and

Fig. 11 is a plan view of still another form of air deflecting cone.

My device comprises a base 1 in which is rigidly mounted an electric motor 2, the armature shaft 3 of which is vertically disposed. On the armature shaft 3 is secured a fan 4 of ordinary construction.

Axially aligned with and located above the fan 4 and the shaft 3 is an inverted air deflecting cone 5, the apex 6 of which is positioned immediately adjacent the plane of rotation of the fan 4.

Secured to the motor casing 2 is a guard 7 comprising an open framework consisting in

the present instance, of heavy gauge horizontally extending wires 8, 8, in which are formed eyes 9 for the reception of retaining screws 10. The wires 8, at the periphery of the guard 7, extend vertically, as shown at 11, to a plane above the fan 4, and thence horizontally, as shown at 12, and are secured, adjacent the apex 6 of the cone 5, to a center plate 13. The vertical guard wires 11 are connected by circular horizontally extending guard wires 14 and 15, to which they are secured in any suitable manner.

Suitably secured to the vertical portions 11 of the guard wires 8 are posts 16, 16. These posts 16 extend vertically above the fan 4 and their upper ends are suitably secured to the horizontally extending flange base 17 of the cone 5, adjacent the periphery thereof. The periphery of the guard below the horizontal wires 12 and the bottom of the guard, below the fan 4, is covered with a suitable wire mesh 18 to prevent any objects from being placed in the plane of rotation of the fan 4. The wire mesh 18 is secured to the guard wires 8, 11, 14 and 15 in any suitable manner.

The truncated conical air deflector 5 thus supported from the motor base so as to position its axis concentric to the motor extends inwardly and downwardly from the substantially horizontal outer portion or base to a maximum curvature at the vertex, whereby air upwardly discharged from the rotating fan will be deflected horizontally without causing back pressure due to eddying adjacent the cone.

The air deflecting cone 5, as shown in Fig. 3, is composed of sheet material suitably pressed into the desired cone shape, providing a cavity 20 in the upper side of the cone, into which may be placed a lamp attachment as shown in Fig. 4, said lamp attachment comprising a base 21 shaped in a manner corresponding to the shape of the cavity 20 of the cone 5. Secured within the base 21 of the attachment is a vertically extending stud or pipe 22 which is adapted to support any desired form of lamp.

Fig. 5 illustrates a flower holder attachment comprising a base 21^a and vertical stud 22^a on the top of which is secured a perforated plate 23 for supporting the stems of the flowers. Obviously water may be placed in the base 21^a to keep the flowers fresh.

Fig. 6 illustrates an ash-receiving attachment consisting of a base 21^b having a verti-

cal stud 22^b on which is secured an ash tray 24.

Figs. 7 and 8 illustrate a modified form of air deflecting cone 5^a in which the portion 5 thereof, adjacent the apex 6^a is corrugated as shown at 25. These corrugations extend radially and as they approach the periphery of the base flange 17^a of the cone 5^a they gradually blend into the plane of said flange.

10 This construction and the constructions shown in Figs. 9 and 11 prevent a swirling of the air under the cone, and direct the air currents in a plane substantially parallel with the base flange of the cone.

15 Figs. 9 and 10 show the cone 5^b as being provided with radially disposed fins or ribs 26 for the purpose above described, and Fig. 11 illustrates the apex 6^c of the cone 5^c as being polygonal in cross section, the flat sides

20 27 thereof blending gradually in the single plane of the base flange 15^c of the cone 5^c.

From the foregoing description of the arrangement of the elements constituting my invention, it will be obvious that as power is supplied to the motor 2 and the fan 4 is rotated the air will be drawn from under the fan and forced against the inverted cone 5 which will deflect the air in a plane substantially parallel to the plane of the table or 30 other support, upon which the device may be placed. The circulation will be approximately as indicated by the arrows in Fig. 1. By this arrangement of elements, the circulation of air will be constant in such plane and in all directions radially disposed with respect to the axis of the fan by means of which all persons seated around the table will be aware of the constant circulation.

40 The air being drawn from under the fan will not disturb any papers which may be lying loosely on the table, thus the device is particularly adapted for use in offices especially where a number of persons are assembled around a table, such as at directors'

meetings, etc. In such an instance, the directors may spread their papers out on the table and at the same time enjoy the circulation of air created by the fan without fear of their papers being scattered.

Obviously any form of speed control for the fan may be installed in the base 1 without departing from the spirit of the invention.

While I have shown a fan consisting of a hub 30 secured to the shaft 3 and having four blades 31, 31 secured to the said hub, each blade being pitched at an angle with respect to the shaft for the purpose of causing a flow of air in a definite direction for the rotation of said shaft in a definite direction, other forms of fans may be employed for causing a similar flow of air without departing from the spirit of the invention.

I claim:

1. A portable fan including a motor, a propeller driven thereby to rotate in a horizontal plane, an air deflecting cone supported in spaced relation to the propeller, and a perforated tubular housing supported in lateral alignment with the propeller and having its upper edge so disposed with relation to the under surface of the cone as to lie in a plane below the emergent stream of air deflected by the cone.

2. A portable fan including a motor base, a propeller driven thereby to rotate in a horizontal plane, a truncated conical air deflector supported from the base with its axis concentric to the motor and having a curved surface varying uniformly from a maximum curvature at the vertex to a minimum at the base and discharging the air horizontally, and a perforated tubular housing supported in lateral alignment with the propeller and having its upper edge so disposed with relation to the under surface of the cone as to lie in a plane below the emergent stream of air deflected by the cone.

WILLIAM H. GINDER.
